E. C. Badger,
Dressing Millstones.

No 11,686.

Patented Sep 19, 1854.

UNITED STATES PATENT OFFICE.

ELLIOT C. BADGER, OF WARNER, NEW HAMPSHIRE.

MACHINE FOR DRESSING MILLSTONES.

Specification of Letters Patent No. 11,686, dated September 19, 1854.

To all whom it may concern:

Be it known that I, ELLIOT C. BADGER, of Warner, in the county of Merrimack and the State of New Hampshire, have invented 5 certain new and useful Improvements in the Mode of Picking and Dressing Millstones; and I do hereby declare that the following is a full and exact description thereof, reference being had to the accompanying drawings and to the letters of reference 10 marked thereon.

The nature of my invention may be thus described; first, I attach a bevel gear wheel to the mill spindle, which turns a pinion 15 and shaft, to which, a cam is attached, and that operates and gives motion to the chisel, or other tool, which is used for furrowing mill stones. The chisel stock or arbor is attached to a perpendicular frame which contains 20 the cam and the stop motion, and the chisel stock is so attached to the frame, that the depth of the chisel is gaged at every blow; the frame that contains the chisel can be moved in any direction by the operator, 25 so that he can dress mill stones with what is called sickle furrows or quarter-dress for threading or cracking. The direction of the chisel over and across the stone, is also moved by a screw, so that every line is 30 alike, the chisel being forced down upon the stone by means of a spiral spring which operates on the arbor that passes down through a nut, by means of which, it can be lengthened or shortened, or turned in any direction, 35 and the movement of the chisel is so arranged by the stop motion, that it can be stopped at any blow or instantly set in motion again, so that in dressing bur stones, it can be stopped and moved over the soft 40 and porous parts, and retained on the harder ones, at the will of the operator.

When the machine is to be put in operation, place it upon the bed stone, the machinery being attached to the spindle, it is 45 at once set in motion by the power that operates the mill. The guards will assist the operator in doing his work in the nicest and the most expeditious manner.

To operate or dress the upper stone, or 50 runner, the machine is moved from the bed stone to the runner which may hang upon the bale, or may be placed upon blocks,—the motion, or power is transferred by two pulleys in a frame with a belt, one pulley being 55 attached to the mill spindle, and the other to the machine.

To enable others to understand the use of my invention, I will proceed to describe its construction and operation:

Figure 1, is a perspective view of the machine, the operations of which are particularly described in the following manner.

Letter A, represents the bed frame or basement which sits upon the mill-stone to be dressed; upon the center of the same is 60 a perpendicular cylinder not seen in the drawings which is firmly attached to the frame or basement aforesaid, about which, the cylinder B and the machinery, operating the machine, acts.

Letter C, represents the guides, as seen in Figs. 2 and 3, which sit upon the basement. In one end of each, there is a circular hole, marked *r*, and at the other end a projection, marked *s*, and when either guide 70 is to be used, the end containing the hole is placed upon the cylinder aforesaid, and it is moved horizontally backward and forward on the bed piece, by means of a threadscrew attached to the bed frame marked I, 75 hereafter described. This screw operates upon the projection on the guide, *s*, by means of a movable nut marked *t*, and the guide is also held in its place by this projection upon it, by the nut and screw, so as to 80 give the furrows or threads their equal distance when cut upon the stone, Fig. 2 representing the guide for the sickle, and Fig. 3 representing that for the straight furrow.

Letter D represents the slide as seen in 85 Figs. 1 and 4 of the drawings, upon the end marked D of which is a firmly fixed frame work to hold the chisel-stock. This slide is moved upon the guide from the center to the circumference and back again 90 as the operator may desire in dressing the stone, it being directed in its movements by a pin or projection marked *v*, as fully seen in Fig. 6, unattached to the slide, near the outer edge of the frame work, which pin 95 plays through the straight or circular slot as indicated by letter *x*, as seen in Figs. 2 and 3.

Letter E represents a revolving shaft and 100 a pinion, which being turned by a gear wheel F, resting upon the cylinder, gives motion to a cam H, and that operates and gives motion to the chisel *u*. The shaft at one end fits into the cam and at the other end into a vertical plate or journal box *d* 105 and that is connected to a horizontal square plate P, made exactly to fill the inner space 110

of the slide in width; upon the center of this square plate is an upright cylinder just fitted to slip onto cylinder B on the frame, as seen in Fig. 7. Thus the slide is kept in its 5 place as it is moved in the groove upon the guide from the center to the circumference of the stone, and back again.

Letter F represents a gear wheel as seen bottom up in Fig. 5, which revolves upon 10 cylinder B, and is attached to the mill spindle by a rod and step, thus when the mill is put in operation this gear wheel gives motion to the pinion and shaft as described in the preceding representation.

15 Letter G represents the frame and the upright stock or spindle attached to the slide as referred to in the representation in letter D, as seen in Fig. 6. The upper end of the spindle is fitted in the frame, and it then 20 passes down through a long nut c, and also through another transverse plate y, upon the upper end of the nut is a shank or projection m which the cam acts on, and gives motion to the spindle. The spindle is further constructed by means of a screw cut 25 upon it so that by turning it in the nut c, the chisel at lower end is lowered or raised at pleasure, and any direction required is gained. Upon the lower end of the spindle 30 is a boss or hub with a slot to receive the chisel or pick, and they are fastened in with a set screw as seen in Fig. 6, letter i, or the 35 pick or chisel may be more easily and firmly fastened into the slot by means of two cheeks fixed on the outer edge of the slot which are 40 pressed against the chisel or pick by a collar, having a screw on the upper part of it, which collar when screwed down confines the chisel or pick very firmly in the slot. Fig. 10 represents the spindle out of the 45 frame work. Fig. 11 represents the lower part of the spindle with the cheeks k and l, the collar being off, and Fig. 12 represents the collar by itself.

45 Letter H, represents the cam, which being turned strikes the projection of the nut m, and raises up the spindle against a spiral 50 spring n, which gives force to the chisel or pick. This spiral spring is upon the upper 55 part of the spindle between the nut and the upper part of the frame, and as the spindle is raised by the cam passing under the projection of the nut, the spring forces down the spindle containing the chisel until it 60 strikes a hub o or large projection on the spindle so as to gage the depth of every blow of the chisel or pick; on each side of the frame are two horizontal handles a, and b, to move the slide containing the 65 chisel or pick back and forth from the center to the circumference. Handle a, is mov-

able, and when raised forces a dog h, against the chisel-stock, so as to stop the movement of the chisel or pick, and by pressing the handle down again in its usual place the 65 spindle containing the chisel or pick immediately commences its movements.

Letter I, represents a screw upon the frame which regulates and moves the guide horizontally upon the frame for threading, 70 or any other operation to be made upon the face of the stone to be dressed or picked.

Letter J represents the rod step and attachments as mostly seen in Fig. 8. The rod passes up through the center of the cylinder of the gear wheel and is attached to the mill spindle so that the gear wheel is put in operation as soon as the motive power is applied to the mill. By means of this rod and attachment the frame or base- 80 ment is also kept in its place and is moved around it upon the stone as a pivot and common center. When the upper or runner stone is to be dressed, it is turned upside down and placed upon the timbers, or it 85 may remain upon the bail.

To commence operations there are two pulleys fitted in a frame at a suitable distance from each other as seen in Fig. 9, and these are connected with a belt, one of which 90 is set over and attached to the mill spindle, and the other to the rod passing through the cylinder of the gear wheel, and the machine is then placed upon the stone to be dressed, and these pulleys are driven by the operation 95 of the mill and the stone is dressed in the same manner as the bed or lower stone.

I contemplate that my improvements may be applied to the picking and dressing the various kinds of mill stones without further 100 explanation, and that it may be modified in various ways without departing from the merits of my improvements, and also may be perhaps applied to the furrowing, picking, and dressing of any stone by one or a 105 gang of picks.

What I claim as my invention and desire to secure by Letters Patent is—

The guide (Figs. 2 and 3) with the narrow slot x in a straight line or such curve 110 as is desired to give the furrow in which a projection from the frame, carrying the pick works, and by which the pick is guided, as it is drawn out to cut the furrow desired; and this either with or without the thread- 115 screw I, by which said guide is moved radially around the cylinder and spindle.

ELLIOT C. BADGER.
